COIN WATER METER

Frederik van der Plas, Bandoeng, Java, Nether-
land East Indies; vested in the Alien Property
Custodian

Application December 4, 1939, Serial No. 307,509
In the Netherlands December 6, 1938

6 Claims. (Cl. 222—2)

This invention relates to a coin controlled water meter in which the water consumption is indicated at all times.

An object of the invention is to provide a simplified and reliable form of construction particularly designed for use in connection with a membrane valve controlling the water supply.

A further object of the invention is to provide a construction in which the water meter controls a revolving plate or bar which in turn controls the valve controlling the water supply.

With the above and other objects in view which will become apparent from the detailed description below, the invention is shown in the drawings in which:

Fig. 1 is a side view with portions in section of the invention as applied to a membrane valve controlling the water supply.

Fig. 2 is a plan view of the construction shown in Fig. 1.

Fig. 3 is a detail view illustrating a modified construction of the control means for the valve.

Fig. 4 is a side view of the control means shown in Fig. 3 with the cooperating valve operating rod.

Fig. 5 is an elevational view with parts in section illustrating the coin control cooperating with the valve operating rod.

Fig. 6 is a cross-sectional view taken on the section line I—I of Fig. 5.

Fig. 7 is a plan view of a modified construction of the control plate shown in Figs. 1 and 2.

Fig. 8 is a side view of the elements cooperating with the control plate shown in Fig. 7.

Fig. 9 is a side view of the construction shown in Fig. 8.

Fig. 10 is an enlarged view of a portion of Fig. 1 showing the valve, and

Fig. 11 is a plan view of the construction shown in Fig. 10.

In the drawings in which similar reference characters refer to like parts in the various views, the usual water meter construction is shown at 1 which is interposed between the water main 6 and the house supply pipe 9 and comprises the usual driving element 15 which drives the consumption dials 12 through the usual transmission 11. Interposed between the water main 6 and the water meter 1 is a valve 5 controlling the water supply from the main to the house pipes. The valve 5 is a membrane valve having a membrane 19 which is usually made of rubber. The other cooperating elements of the valve will be described below.

Also controlling the water main 6 is a stop cock 7 and the direction of flow of water is

indicated by the arrow 8. A coupling 4 connects one end of the water meter to the valve housing.

The control means for operating the valve 5 will now be described. This comprises a flat plate 2 secured to the vertical shaft 3 which is rotatably mounted upon the bracket 13 which in turn is secured at one end to the water main 6 and at the other end to the coupling 4. The shaft 3 is rotated by the water meter by means of the gears 14 and the shaft 10 thereby rotating the plate 2 in accordance with the consumption of water in the house.

A small aperture 16 is provided in the plate 2 as shown in Fig. 2 which is designed to cooperate with a valve controlling rod 17. The rod 17 is fixed to a valve 18 which controls the flow of water into the space between the rod 17 and the housing 48 and thence through the pipe 61 to a point in back of the wall 62 of the valve 5. When the control rod 17 is urged downwardly by the plate 2 which occurs when the top of the rod 17 is not seated in the aperture 16, then the valve 18 is also urged downwardly thereby permitting the water to flow in the manner indicated through the pipe 61 to a point in back of the wall 62. When the valve 18 is in such position then the membrane 19 is also open and the water will flow from the water main 6 to the point 64 at the other side of the valve 5 as indicated by the arrow 63 in Fig. 1 between the wall 62 and the membrane 19. Also when the membrane is open the water will flow through the small opening 20 provided in the membrane 19 into the space 21 below the membrane and through a passage 59 into the space 60 and then passes the valve 18 to the pipe 61.

However, when the control rod 17 is urged upwardly into the aperture 16 by means of the spring 65 the valve 18 closes the water flow through the pipe 61. Then the pressure in the space 60 and the space 21 will be equalized to the water pressure in the main 6 and in such case the membrane 19 will be urged upwardly against the lower edge of the wall 62 and the flow of water will be stopped.

When the control rod 17 is forced out of the recess 16 and thereby forced downwardly, the water supply will again be opened. This action of the control rod 17 is brought about by the coin controlled mechanism shown particularly in Figs. 5 and 6.

The quantity of water supplied for a particular coin is fixed by one revolution of the plate 2. Also the amount of water supplied may be ad-

justed to any desired quantity by providing suitable gearing between the shaft 3 and the water meter transmission 11.

The coin control for the valve controlling rod 17 will now be described. This coin control is particularly shown in Figs. 5 and 6. A channel 22 for the coin is located between the guide bars 23 and 24 which in turn are located between the front plate 25 and the back plate 26. Upon dropping a coin in the channel 22 such coin will come to rest upon a fixed bar 27 and one arm of a double-armed lever 28 pivotally mounted on a pin 29 fixed to the back plate 26. The other arm of the lever 28 is pivotally connected to the control rod 17 by means of a pivot 30. The lower edge of the arm of the lever 28 cooperating with the coin is bent in such a manner that the coin may be held thereby. A spring 31 bears against the lower edge of the coin arm of the lever 28 and tends to raise such arm upwardly which causes the control rod 17 to bear constantly against the plate 2.

In Fig. 5 a coin is shown at 42 illustrating the manner in which it rests on the bar 27 and the coin arm of the lever 28 while the valve controlled rod 17 is positioned in the recess 16 of the plate 2 thereby cutting off the supply of water through the valve 5 in the manner above described.

In order to secure a new supply of water and remove the control rod 17 from the recess 16 as shown in Fig. 5, the button 32 on the slide 33 is pressed inwardly. The slide 33 contacts the coin 42 with its lower front bevelled edge and pushes the coin against the coin arm of the lever 28 thereby pivoting the lever 28 about the pin 29. This pivoting of the lever 28 causes a downward movement of the control rod 17 thereby releasing the plate 2. When the space between the coin arm of the lever 28 and the bar 27 is sufficiently wide the coin will drop down into a coin box, not shown.

The downward movement of the valve control rod 17 is just sufficient to release the plate 2 and in the manner above described the membrane 19 will be opened in the valve 5 and the water passing through the meter will revolve the driving element 15 and thereby remove the recess 16 from alignment with the control rod 17. The membrane 19 of the valve 5 will therefore remain open until the plate 2 makes a complete revolution when the recess 16 will be again aligned with the control rod 17.

The means for returning the slide 33 to its original position after being depressed, is shown in Figs. 5 and 6. This comprises a bracket member 36 which secures a tubular element 37 to the plates 25 and 26. The tubular element 37 houses a spring 38 which at one end, the left-hand end, as shown in Fig. 5, contacts the closed end of the tubular element 37 and at the other end bears against a disk 39 which is fixed to a rod 40 carried by the slide 33. The rod 40 projects at right angles to the slide 33 and extends through a groove 41 provided in the tubular element 37. Upon depression of the button 32 with a consequent movement of the slide 33 to the left as shown in Fig. 5, the spring 38 will be compressed and upon release of the button 32 such spring acting against the disk 39 will return the slide 33 to its original position.

In Figs. 3 and 4 a modified construction for the plate 2 is shown in which there is provided a cylinder 42 rotating about a horizontal axis. The cylinder 42 is fixed to the shaft 68 which

carries a worm gear 70 which meshes with a gear 69 fixed upon the shaft 3. The cylinder 42 is provided with an aperture 16' which cooperates with the control rod 17 in exactly the same manner as the aperture 16 in the plate 2 of the modification above described.

A further modified construction for the control plate 2 is shown in Figs. 7, 8 and 9, wherein a spiral groove 71 is provided on the under-surface of the plate 2 for a pin 58 carried by a slide 57 which reciprocates upon a plate 72 mounted on the top of the control rod 17. The slide 57 is connected to the plate 72 by a spring in the manner shown particularly in Fig. 17. The operation with this modification is essentially the same as that described with reference to the modification shown in Figs. 1 and 2.

What I claim is:

1. A coin controlled water meter comprising a measuring device, a transmission actuated by said water meter, a membrane valve, a control valve for said membrane valve, a control rod for said control valve, a coin control for said rod, a plate operated by said transmission also controlling said rod, said plate having a helical groove therein and a recess cooperating with said rod.

2. A measuring device comprising a water meter, a plate rotated by said water meter in proportion to the amount of water passing therethrough, a valve for controlling the water flow through said meter, an axially movable rod eccentrically of and parallel to the axis of rotation of said plate for opening and closing said valve, and means for normally urging one end of said rod into engagement with one face of said rotating plate, said plate face having an aperture therein located in the path of engagement between the plate and the rod, whereby the end of said rod will be urged into said aperture to lock said plate against rotation and prevent overrunning movement of the device and also to simultaneously close said valve when the plate has rotated through a predetermined angle, and means to withdraw said rod from said locking engagement to initiate the operation of said device.

3. A measuring device comprising a water meter, a plate rotated by said water meter in proportion to the amount of water passing through said meter, a valve for controlling the water flow through said meter and an axially movable rod for opening and closing said valve, said rod yieldingly engaging one face of said rotating plate, and said plate face having an aperture therein located in the path of engagement between the plate and the rod, whereby the end of said rod will be urged into said aperture to lock said plate against rotation and prevent overrunning movement of the device and also to simultaneously close said valve when the plate has rotated through a predetermined angle, and control means to withdraw said rod from said locking engagement to initiate the operation of said device.

4. A measuring device comprising a water meter, a transmission actuated by said water meter, a plate rotated by said transmission in proportion to the amount of water passing through said meter, said plate having an eccentrically located aperture in one face thereof, a valve for controlling the water flow through said meter, and an axially movable rod, one end of the rod operatively connected to said valve and the other end of the rod yieldingly engaging said face of the plate along the same circle upon

which said aperture is located whereby the end of said rod will be urged into said aperture to lock said plate against rotation and prevent overrunning movement of the device and also to simultaneously close said valve when the plate has rotated through a predetermined angle, and means for withdrawing the end of said rod from said aperture to initiate starting of the device.

5. A measuring device comprising a water meter, a plate rotated by said water meter in proportion to the amount of water passing therethrough, said plate having a helical groove in one face thereof, an axially movable rod for opening and closing said valve, a slide member carried by said rod, means for normally urging said slide member into engagement with said

groove to control the closing operation of said valve, means for withdrawing said slide means from said groove in a direction normal to said plate face to thereby initiate operation of the device, and a spring for normally urging the slide in a direction substantially parallel to said plate face to an initial position.

6. A measuring device according to claim 2 in which a helical path of engagement is provided between said plate and rod, and in which the engaging end of said rod is mounted upon a slide member, said slide member being movable back and forth in a plane substantially parallel to said plate face.
